[57] CLAIM

The ornamental design for a stand for a point-of-sale terminal, as shown and described.

DESCRIPTION

FIG. 1 is a left side and front perspective view of a stand for a point-of-sale terminal showing my new design;

FIG. 2 is a top plan view thereof;

FIG. 3 is a left side elevational view thereof;

FIG. 4 is a front elevational view thereof;

FIG. 5 is a rear elevational view thereof; and

FIG. 6 is a right side elevational view thereof.
